Primary Examiner — Jennifer Rivard*Assistant Examiner* — Jennylou M Binas(74) *Attorney, Agent, or Firm* — von Briesen & Roper, s.c.(57) **CLAIM**

The ornamental design for a cleaning tool, as shown and described.

DESCRIPTION

FIG. 1 is an isometric view of the cleaning tool showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a rear elevational view thereof; and,

FIG. 7 is a bottom plan view thereof.

The surface shade lines along the top of the handle is to show the contour of the handle. The dots along the lower portion of the cleaning tool represents a contrast in appearance.
